UNITED STATES PATENT OFFICE

2,579,960

METHOD OF MAKING ARTIFICIAL DENTURES

František Pita, Jirkov, and Julian Prokeš,
Chomutov, CzechoslovakiaApplication July 21, 1949, Serial No. 105,931
In Czechoslovakia May 26, 1949

1 Claim. (Cl. 18—55.1)

1

Artificial dentures are known which comprise an artificial gum adapted to be placed in position on the natural gum, the seating face of the denture being provided with one or more depressions so arranged as to form cavities between the contacting faces of the artificial gum and of the natural gum, the air being exhausted by means of a non-return valve from the cavities so formed. Round studs project from the denture into the cavities in the seating face in such a way that the front faces of the studs abut against the tooth area of the natural gum and are moderately pressed into the latter.

In accordance with a prior invention of the same inventors the cavities or depressions between the contacting faces of the artificial and natural gums are formed by means of suitable interposed elements during the corresponding phase of the process of making the denture. The interposed elements may be originally flat and made of a soft foil, preferably a lead foil. The interposed elements have a contour and a cross-section of suitable shape and are provided with circular or oval openings, a pair of interposed elements for the right hand and left hand sides of the denture being obtained by dividing into halves a previously made integral piece.

In the making of dentures according to the method just referred to, it has been found that it is not convenient in all cases to divide the foil and that more particularly in the case of irregularly formed gums, especially if the latter are not symmetric with respect to the vertical plane, it is rather difficult to obtain, by means of such two-part foils, cavities in the seating face of the denture in such a way as to comply with the requirements.

The invention described hereinafter permits to overcome the just mentioned difficulty. In accordance with the invention a single foil is employed to shape the cavities for the whole denture, the said foil being provided with slots preferably extending from the circular or oval openings in the foil to the edge of the latter. Experience has shown that by means of foils which have been shaped as described either during their manufacture or supplementally before their use, it is possible to obtain very easily the required cavities not only in normal cases but more particularly also in the case of abnormally formed gums.

For a more detailed description of the invention reference is made to the accompanying drawings, which show an example of the foil and of its utilisation in the method according to the present invention. In the drawings

2

Figure 1 is a section through a lower complete denture and the corresponding part of the lower natural gum along the line A—B of Figure 2;

Figure 2 is a bottom view of the denture shown in Figure 1, the cavities being formed by means of a two-part foil as hitherto used;

Figures 3 and 4 are cross-sections at an enlarged scale through the cavities between the contacting faces of the artificial and the natural gums;

Figure 5 is a plan view of a foil as hitherto used;

Figure 6 is a plan view of a foil provided with slots in accordance with the present invention;

Figure 7 is a plan view of the model of a normal gum on which a foil in accordance with the present invention has been fastened; and

Figure 8 is a similar plan view of the model of an abnormally formed gum.

20 The artificial denture shown in Figures 1 and 2 comprises an artificial gum 1 which is adapted to be placed in position on the natural gum 2. Artificial teeth 3 are embedded in the gum 1. Between the seating face of the artificial gum and the surface of the natural gum the artificial gum has provided therein a series of cavities 4 which are interconnected and distributed along the entire tooth face of the natural gum and to which a non-return valve 5 is connected. At locations intermediate of the cavities 4 the seating face of 25 the artificial gum 1 is provided with round studs 6 which are moderately pressed into the natural gum 2 when the artificial gum 1 is placed in position on the latter. The cavities 4 have an undulated contour in plan view and their cross-section has the shape of a trapezoid as it appears from Figures 3 and 4 which show cross-sections through these cavities at the location of a stud 8 (plane C—D in Figure 5) and intermediate two adjacent studs 6 (plane E—F in Figure 5), respectively, assuming that the seating face has been straightened to a plane.

40 The above mentioned valve 5 may be constructed preferably in the manner described and shown in the co-pending application Serial Number 105,932 filed July 21, 1949, now abandoned, and relating to an "Artificial Denture."

45 During the production of a denture by the prior method, the cavities 4 shown in Figures 1 and 2 are modeled on the seating face of the denture by means of a foil, such as that shown in Figure 5, provided with circular openings 8 which correspond to the aforementioned studs 6. In the production of, for instance, a complete denture the foil is cut transversely in the plane G—H and the 50 two halves after their adaptation to the shape of

a gum are fastened on the model of the gum whereby the cavities shown in Figure 2 are obtained.

However, the just mentioned adaptation of the two halves of the foil shown in Figure 5 to the shape, and more particularly to the irregularities, of a gum causes difficulties in some cases.

Now it has been found that the manipulations are substantially facilitated under all practical circumstances, if a foil of this type is provided with slots 9 as is shown in connection with the foil 10 in Figure 6. In a preferred arrangement the slots 9 connect the inner circular openings 8 of the foil with the edge of the latter. The slots 9 may be all of them on the same side, as shown in Figure 6, or alternately on either side as shown in Figure 7.

If the foil is provided with such slots 9 during the manufacture of the same, it is preferable to arrange a slot for each of the circular openings 20 8, except for the two end openings of the series. If, on the other hand, the slots are formed preparatory to the application of the foil, it is possible to provide the slots only at such locations where they are necessary for the easy adaptation 25 of the foil to the gum.

The foil is applied in the same way as in the prior method on the surface of, for instance, a plaster model 11 (cf. Figure 7) of the natural gum and is carefully adapted to the form of the latter. This adaptation, which is very important for a satisfactory operation of the denture to be produced, is facilitated by the slots 9 provided in accordance with the present invention. For the adaptation, the foil 10 is fastened on the model 30 11, for instance, by means of small nails 12 and the further operations are carried out in the conventional manner.

Certain toothless natural gums in which a denture is to be mounted have irregular depressions 40 while others again have not a regular contour in plan, being deformed from one of their sides. In such cases the foil in accordance with the invention is most convenient. Figure 8 shows by way of example the model 13 of such a natural gum whose arc is not symmetrical, as the gum

is deformed in its left hand part. The drawing shows clearly that the foil 14 can be easily adapted to such a gum.

It is possible, of course, to make the slots in the foil according to the present invention in a manner different from that shown and described and still obtain the aimed results. Thus, it is not necessary for the slots to be cut transversely. They may be inclined to the corresponding transverse planes or may be cut in any other suitable manner.

What we claim is:

In the method of molding dentures with suction depressions in the gum seating surfaces thereof with the aid of a foil strip of the size and general shape of the depressions to be formed and having apertures at spaced intervals, the improvement which comprises slotting the foil strip from the apertures therein to one edge thereof, applying the thus slotted foil strip to the mold of the gum and deforming it to conform it to the contour and shape of the mold of the gum in the position thereon at which the depressions are to be formed in the denture and molding the denture in contact with the mold of the gum with the foil strip applied thereon.
